UNITED STATES PATENT OFFICE

131,468

DESIGN FOR A PORTABLE RANGE

Styles T. Howard, Jeffersonville, Ind.

Application April 24, 1941, Serial No. 100,611

Term of patent 3½ years

To all whom it may concern:

Be it known that I, Styles T. Howard, a citizen of the United States, stationed at Jeffersonville Quartermaster Depot, Jeffersonville, Indiana, residing at 710 E. 9th St., Jeffersonville, in the county of Clark and State of Indiana, have invented a new, original, and ornamental Design for a Portable Range, of which the following is a specification.

Reference being had to the accompanying drawings forming a part thereof:

Fig. 1 is a perspective view showing the front and one side of the portable range.

Fig. 2 is a perspective view showing the rear and the side opposite to the one shown in Fig. 1.

I claim:

The ornamental design for a portable range, substantially as shown.

STYLES T. HOWARD.
